UNITED STATES PATENT OFFICE.

PHIL DAVIES, OF WOOLLAHRA, NEW SOUTH WALES, AUSTRALIA.

DEVICE FOR REPLACING FUSE WIRE AND FOR INDICATING BLOWN-OUT ELECTRIC CIRCUITS.

Application filed December 9, 1919. Serial No. 343,588.

To all whom it may concern:

Be it known that I, PHIL DAVIES, subject of the King of Great Britain and Ireland, residing at 112 Oxford Street, Woollahra, in 5 the State of New South Wales, Commonwealth of Australia, have invented new and useful Improvements in a Device for Replacing Fuse Wire and for Indicating Blown-Out Electric Circuits, of which the 10 following is a specification.

The object of this invention is to provide a fuse replacing appliance which is efficient and so simple to operate that any ordinary unskilled person may install a new fuse by 15 merely turning a handle. The main features are that (1) it is practically impossible to insert a fuse wire to carry a heavier current than that for which the appliance is intended (2) should the fuse "blow" the fact 20 is immediately revealed by an indicator on the face of the appliance (3) a fresh supply of fuse wire may be quickly inserted, the spool being so constructed that it is impossible to insert it in the appliance in any but 25 the right way and (4) only a spool box especially constructed for this appliance can be used.

The appliance consists of a box, of suitable size, shape and material, in which is 30 a rotatable block and a spool box, the latter having two projecting curved arms, one on either side, the extremities of these curved arms being turned over in such a way as to form channels in which the free end of the 35 fuse wire may be loosely held in position ready for the appliance to be operated. The rotatable block is approximately oval in shape the underside having a centrally situated circular boss that is seated within a 40 washer-like member formed in the bottom of the box. A portion of the wall of this washer-like member forms a ratchet which permits the block to be rotated in one direction only, the next section being plain, while another, smaller, portion of the wall is cut away to form an indentation to accommodate the foot of a transverse spring-operated stop which is forced out by the action of the 45 spring when it is released by the fuse wire blowing. Partially surrounding the washer-like member and of larger internal diameter, 50 is a narrow platform or second washer-like member, one portion of which is provided

with an incline leading from the upper surface of the first washer-like member to 55 the upper surface of the second washer-like member or platform, while another portion of the second washer-like member is provided with an incline leading down from the upper surface of the platform to the upper 60 surface of the first washer-like member. Diametrically opposite disposed pole pieces extend through both washer-like members. These pole pieces are secured in the base of 65 the box, the electrical connection being made on the underside of the base of the box, the upper ends of the pole pieces lying flush with the surface of the platform or second washer-like member.

The rotatable block revolves upon a spindle rigidly secured to the base of the box, and consists of two main parts, viz:—an upper and lower part. Near each end of the block is a plunger operated by a spring which causes the plunger to make a continuous rubbing contact along a portion of the platform and a portion of the first washer-like member and forces the plunger out of action when it passes the second pole piece and at that point releases the loose piece of 70 wire which has been fused and which will drop out through an opening provided for the purpose in the wall of the box. At each 75 end of the rotatable block is a slot formed by cutting away a portion of the underside 80 of the upper part of the block. The gripping end of the plunger lies normally flush with the upper face of the lower part of the block. The plunger will be forced into one of the slots as it passes up the incline 85 on to the platform.

It will be assumed that the appliance is ready for use and that it is desired to insert a fuse in the electrical circuit. The handle is given a half turn in the direction of the 90 hands of a watch. As the block is rotated one of the plungers will come into contact with the incline leading up to the upper surface of the platform. The fuse wire that is stretched from one arm of the spool 95 box to the other has now entered the slot in the end of the block and is lying immediately over the end of the plunger, so that as the block is rotated the plunger is gradually raised by the incline and being forced 100 up into the recess in the upper part, carries 105

with it and firmly grips the fuse wire that is stretched from one arm of the spool box to the other arm, pulling the free end out of the channel in one arm on the spool box 5 and drawing it through the channel on the other arm from the spool within the spool box. As all the parts have not yet been brought into operation the handle will in this case fly back taking with it the pointer 10 to the "off" position. The handle is then given a second half turn and the block being thereby rotated will first bring the foot of a transverse spring-operated stop, against the plain portion of the wall of the 15 race forcing it in and holding it until the wire is gripped by the second plunger. The foot of the stop is then opposite the indentation in the inner edge of the first washer-like member but is prevented from 20 entering that indentation by the fuse wire which is gripped tightly by the plungers at the opposite ends of the block. In this position the tail of the transverse stop is projecting beyond the other side of the block 25 and abuts against a stud projecting upwardly from the base of the appliance close to the inner edge of the first washer-like member, thus forming an independent stop to the rotation of the block. The plungers 30 are now immediately over and in vertical contact with the two poles in the platform or second washer-like member, the two being in electrical connection through the fuse wire that is gripped by them. The foot of 35 a second transverse stop, situated on the other side of the minor axis of the block, is now in engagement with the ratchet in the wall of the race, thus preventing the block from being rotated in a backward direction. 40 Leaving the appliance in this position and passing to the means for operating it, a handle provided with a pointer is mounted upon a spindle, upon which the rotatable block revolves, and secured by means of a 45 screw. The handle is provided with a short hollow boss which passes through an opening in the lower half of the lid of the box. This opening is made by cutting two concentric semi-circles so that the movement 50 of the handle may be limited to a half turn by means of a stud projecting from the under side of the pointer. The inner end of the hollow boss is made square, the square portion engaging with a rectangular lever 55 plate having shallow walls. This lever plate revolves upon the block spindle, the hole through which the spindle passes being close to one end of the plate. The sides at the other end of the plate are adapted to 60 engage with stops as hereafter described. Surrounding the spindle, between the under side of the handle and the lever plate, is a coil spring adapted to rotate the lever plate and handle backward when the plate is 65 released by the transverse stop that is forced

out by the action of the spring when the fuse wire blows, the foot of the stop entering the indentation in the inner edge of the first washer-like member.

On each side of the minor axis of the rotatable block and diagonally opposite one another are two rigid stops having inclined leads to their faces. When the appliance is set, the long end of the rectangular lever plate is seated between the right stop and the upper end of the transverse spring-operated stop. It is then impossible to turn the handle in either direction because the stud on the underside of the indicator hand prevents it from being turned forward while the fuse wire gripped between the plungers is holding one of the transverse spring-operated stops in the forced back position, the head of such stop being in engagement with the rectangular lever plate, the foot of the other transverse stop being in engagement with the ratchet in the first washer-like member at the bottom of the box thus preventing any backward movement. When an overload occurs and the fuse blows, the transverse stop that was held by the fuse wire is released, its spring forcing it outwards into the recess in the first washer-like member, the rectangular lever plate, being operated by its spring is rotated backward carrying with it the operating handle and indicator hand, is forced up and over the inclined lead on the rigid stop, drops down and is held in engagement with the upper end of the other transverse stop. The 100 foot of this transverse stop is then in engagement with the ratchet in the race. In this position the indicator hand is pointing upward showing that the fuse has blown and is ready for a new fuse to be placed in 105 circuit by giving the handle a half turn.

In order that the invention may be more clearly understood reference will now be made to the accompanying sheet of drawings in which:—

Fig. 1 is a perspective view of the fuse replacing appliance showing the indicator hand in the "unset" position.

Fig. 2 is a similar view of the appliance showing the indicator hand at the "unset" 115 position, certain parts being broken away to illustrate portions of the internal mechanism.

Fig. 3 is a front view of the appliance with the cover removed and a part shown in 120 section.

Fig. 4 is a central vertical sectional view of the appliance with certain parts shown in side elevation.

Fig. 5 is a front view of the block and 125 wire spool, illustrating the manner in which the wire carried by the spool is gripped by the block.

Fig. 6 is a detail sectional view illustrating the manner in which one of the adjust- 130

able stops functions to hold the block in adjusted positions.

Fig. 7 is a perspective view of the appliance with the front cover, the internal block 5 and other parts removed.

Fig. 8 is a perspective view of the cover.

Fig. 9 is a perspective view of the inner or lower portion of the block.

Fig. 10 is a similar view of the upper portion of the block.

Fig. 11 is a view similar to Fig. 9 but showing the adjustable stops and the block supporting spindle removed from the block.

Fig. 12 is a perspective view of the adjustable stops.

Fig. 13 is a perspective view of the operating handle, indicator pointer, handle operated lever and the spring of the handle operated lever.

Fig. 14 is a perspective view of the special form of spool employed in the improved apparatus.

Fig. 15 is a perspective view of the casting partly broken away to show the washer-like members.

Fig. 16 is a central vertical sectional view of the appliance.

Fig. 17 is a detail sectional view illustrating one of the fuse wire engaging plungers. 1 is the box, 2 the upper half of the cover thereof which is secured in position by a milled nut 3, the handle 5 being kept in position by the screw 6. The lower half of the cover 4 will be provided with lugs 7 by which to secure it to the box by means of screws 8. Two concentric semi-circular apertures 9 and 10 are cut in the lower half of the cover, the point of junction between the two semi-circles forming shoulders 11 thus forming a stop to limit the movement of the handle. The handle is provided with a pointer 12, on the inner side of which is a pin 13 that engages with the shoulder stop 11 thus limiting the movement of the handle 45 to a half turn. At the rear of the handle and integral therewith is a hollow boss 14 the extreme end 15 of which is made square.

Upon the base within the box is a washer-like member 16 the inner edge of which is divided into three sections the ratchet 17, plain section 18 and indentation 19. Partially surrounding and upon the wall of the member 16 is a second washer-like member 20 having an outside diameter equal to that of the member 16 but whose inside diameter is larger than the inside diameter of said member 16. The upper end of the inner edge of the member 20 is inclined to form an incline 21 leading from the upper surface of the member 16 to the upper surface of the member 20. A similar incline 21^a leads from the upper surface of the member 20 down to the upper face of the member 16. The member 20, as shown in Fig. 16, is connected to the pole pieces 22

by means of which the appliance is placed in the electric circuit in a manner well known and understood. The inner ends of the pole pieces 22 are flush with the outer surface of the platform 20.

70

A rotatable block 23, formed of inner and outer sections 25, 24 and a circular boss 26, is arranged within the casing 1, and the boss 26 is seated within the members 16 and 20 and these sections and the boss are axially secured in position by the spindle 27 upon which they and the handle 5 rotate. In the inner part 25 of the block 23 are two parallel slots, one on either side of the spindle, in

75

which are transverse stops 28 operated by springs 29 and each provided with a head 30 adapted to engage with a lever plate 31. Each of the stops also has a long leg 32,

80

which engages with the different sections of the inner edge of the member 16, and a short leg or tail piece 33, the function of which is to engage with the stop 34 projecting from the upper portion of the member 16. The springs 29 are held in compression between

85

shoulders 35, in the transverse stops 28, and cross pieces 36 let into the upper surface of the inner part 25 of the rotatable block. Near the ends of the section 25 are recesses

90

37 in which are secured, in any suitable and convenient manner, plungers 38 provided with sleeves 38^a composed of a suitable insulating material, and collars 39, such plungers being operated by springs 40. The underside of the outer section 24 of the rotatable block is cut away to a certain depth

95

at each end so as to form recesses 40^a through which the fuse wire 42 will pass to be held by the plungers 38 as the latter are forced out by passing up the incline 21 on to the member 20. While the lower end of the

100

plunger is travelling over the member 20 it continues to grip the fuse wire but immediately it passes over the incline 21^a in which the platform terminates, it is free to be forced out by the spring 40 thus releasing

105

the short piece of wire remaining after the fusing has taken place, and this short piece of wire will drop out through the cut away portion 43 in the wall of the box.

The upper part 24 of the rotatable block 115 is provided with slots 24^a on either side of the axis, and diagonally opposite one another. The heads 30 of the transverse stops 28 project into and above these slots, it being the projecting heads that engage with the

120

rectangular lever plate 31. On the upper surface of the part 24 of the block 23 are two stops 44 having inclined leads to their faces. One of these stops 44 is opposite to the heads 30 of each of the transverse stops 28. Referring to Fig. 3 of the drawings the appliance is shown set, the fuse having been placed in the electric circuit. When an overload takes place the wire will fuse at some point between the two plungers by which it

130

is gripped thus releasing the head 30 of the stop 28 which is forced outwardly by the spring 29, the foot 32 enters the indentation 19 at the same time drawing with it the short 5 leg or tail piece 33 which is thereby freed from the stop 34; the head 30 having been forced out by the spring 29, releases the lever plate 31 which is rotated in an anti-clockwise direction by the action of the helical 10 spring 45 on the spindle 27 and in its travel backwards the long end of the lever plate 31 passes up and over the inclined surface of the stop 44 until it abuts against the head 30 of the other transverse stop, in which 15 position it will be forced down between the two stops by the helical spring 45 and the appliance is then ready for a new fuse to be placed in the circuit. This is done by giving the handle 5 a half turn as hereinbefore 20 described, the lever plate being then in engagement with the face 46 of the stop 44 the rotation of the handle, and with it the lever plate, will cause the block 23 to rotate with them in a clockwise direction.

25 The spool box 47, in which is the spool 48, is secured upon a pin 49 and is provided with curved arms 50, the outer peripheries of which are adapted to lie close to the inner wall of the box 1 in order to prevent the 30 spool box and arms from moving in order that only a spool box specially constructed for this appliance and which will carry the correct fuse wire may be inserted in the appliance, the outer periphery of one of the 35 arms 50 is provided with a recess 53 which engages a projecting tooth 54 integral with the wall of the appliance. Upon the spool 48 is wound a suitable supply of fuse wire 42 the free end of which passes out through an 40 opening in the side of the box, through the channel formed by the turned over portion 51 of the arm 50 and from thence to the channel formed by the turned up portion 52 of the other arm 50 by which it is lightly 45 gripped ready for the appliance to be brought into operation.

The spool box 47 is intended to be a metal stamping and will be closed or sealed after the wire spool has been inserted in the box. 50 It will be noted from the drawings that the spool box is integral with the arms 50, and it would therefore be necessary to destroy the box in order to place fresh wire upon the spool. All spools carrying fuse wire of 55 a given gauge will be provided with arms having the recess 53 placed in proper position for operation with the member 54, and this latter member will always be in the same position on all appliances intended to 60 carry up to a given load. Consequently the spool box may only be replaced by a similar spool box carrying a wire of the same gauge.

I claim:—

1. In a device for replacing fuse wire and 65 for indicating blown out electric circuits,

a spool and spool box adapted to carry a coil of fuse wire, two curved arms integral with the spool box, one of said arms being provided with a recess, a corresponding tooth to fit into the recess, and means on the arms 70 through which the fuse wire may be threaded and held stretched from one arm to the other for the purpose herein described.

2. In a device for replacing fuse wire and for indicating blown out electric circuits such as is herein described an indicator hand or pointer integral with a handle for operating the appliance and a spring operated lever plate for the purpose specified. 75

3. In a device for replacing fuse wire and for indicating blown out electric circuits, an indicator hand or pointer integral with a handle for operating the appliance and means for automatically returning the handle to the operative position for the purposes specified. 85

4. In a device for replacing blown out electric circuits, an approximately oval shaped two piece rotatable block, stops on the rotatable block adapted to engage with a lever plate, the ends of the rotatable block being provided with slots through which the fuse wire may pass, transverse cam-operated plungers that grip the wire within the slots as the block is rotated, such plungers having sleeves of suitable insulating material and being adapted to make contact with the pole pieces in an electric circuit for the purposes specified. 90

5. In a device for replacing fuse wire, a wire holding spool and means for supporting a portion of the wire which has been withdrawn from the spool, a member automatically actuated in one direction and manually actuated in the opposite direction and provided with means for engaging the wire, and means for disengaging the last named means from the wire when said member is actuated. 105

6. In a device for replacing fuse wire, a spool support, a sealed spool box engageable with said support and carrying a spool of fuse wire, and cooperating means provided on the support and spool box to permit the spool to be placed on the support, one of said means functioning to prevent spool boxes other than a uniform type from being placed on the support. 115

7. A device for replacing fuse wire comprising a wire holding spool and means for supporting a portion of the wire which has been withdrawn from the spool, a rotatable block provided with a plurality of gripping members designed to engage and grip the wire, means for forcing said gripping members out of operative position to permit the same to release the wire, means actuated during rotation of the block for causing the 120

- gripping members to grip the wire automatically operated means for moving the block in one direction, and manually actuated means for moving the block in an 5 opposite direction.
8. A device for use in replacing fuse wire and for indicating blown out electric circuits comprising a casing provided with superposed inner and outer washer-like 10 members, the inner member having its inner edge shaped to provide a segmental ratchet, a curved portion and an indentation, a fuse wire support located in the casing, a block rotatably mounted in the casing and provided with grippers for the fuse wire, spring actuated stops carried by the block and each designed to engage the fuse wire at a point between the grippers, said stops cooperating with the ratchet segment 15 to prevent the block from rotating in one direction only, the indentation being adapted to permit movement of each stop under the influence of its spring when said stop is released by the breaking of the wire between the grippers, and means for rotating 20 25
- the block to bring successive stops into engagement with the fuse wire.
9. A device of the kind defined by claim 8 in which the outer washer-like member is provided with inclined surfaces designed to engage the grippers to force the same into engagement with the wire and springs for releasing the grippers from the wire.
10. A device of the kind defined by claim 8 in which the outer washer-like member is provided with oppositely disposed inclined surfaces which lead from the outer surface of the inner washer-like member to the outer surface of the outer washer-like member, and springs engaging said grippers and normally pressing on the same to cause the grippers to release the wire, said grippers co-operating with the washer-like members and the inclined surfaces to grip the wire when the grippers engage one of said inclined surfaces.

In testimony whereof I have signed my name to this specification.

PHIL DAVIES.
